UNITED STATES PATENT OFFICE.

CHARLES W. PIERCE, OF HARTFORD CITY, INDIANA.

MAIL-BAG RECEIVING AND DELIVERING APPARATUS.

1,321,327.

Specification of Letters Patent.

Patented Nov. 11, 1919.

Application filed May 19, 1917. Serial No. 169,730.

To all whom it may concern:

Be it known that I, CHARLES W. PIERCE, a citizen of the United States, residing at Hartford City, in the county of Blackford 5 and State of Indiana, have invented certain new and useful Improvements in Mail-Bag Receiving and Delivering Apparatus, of which the following is a specification.

This invention is a mail bag receiving 10 and delivering apparatus and has for its principal object the production of a device which is adapted to be carried upon a railway car adjacent the door opening whereby bags of mail may be delivered from and received by the device.

Another object of this invention is the production of a mail bag receiving and delivering apparatus which includes a movable frame carried at the door opening of a railway car, thus permitting the device to be retracted into the interior of the car when desired, although when a bag of mail is to be delivered therefrom and another bag received thereby, the frame may be swung to 25 project the delivering and receiving members beyond the outer portion of the car.

A still further object of this invention is the production of a mail bag receiving and delivering apparatus, which includes a pair 30 of gripping members carried upon the movable frame, each gripping member comprising a fixed jaw and a movable jaw together with means for forcing the movable jaw toward the fixed jaw.

One practical form of construction and assembly of the present invention will be hereinafter described and is illustrated in the accompanying drawings, in which:—

Figure 1 is a fragmentary top plan view 40 of a railway car, the gripping members being shown in top plan and illustrating how the same project beyond the outer portions of the car.

Fig. 2 is a section taken on the line 2—2 45 of Fig. 1.

Fig. 3 is a fragmentary interior view of a railway car, showing the receiving and delivering apparatus in condition for use and illustrating a rear elevation thereof.

In the preferred embodiment of the present invention about to be described, for the purpose of illustration, a railway car of any conventional form is disclosed fragmentarily at 5 and has a door opening 6 provided 50 with the usual jambs 7 and 8.

The frame of the mail bag receiving and

delivering apparatus comprises vertically extending end beams 9 and 10 to which the ends of the upper and lower horizontally extending beams 11 and 12 are secured in any desired manner. Thus a substantially rectangular frame is provided and it should be understood that it is to be of a substantially rigid construction. Hinges 13 are secured to the jamb 7 and also to the vertical end beam 9 and the upper horizontal beam 11 as illustrated in Fig. 3 thus hingedly supporting the frame upon the jamb 7. Accordingly when the device is not to be used it may be swung to the interior of the car 5 and therefore will not obstruct the door opening 6. However, when swung to an operative position the frame will extend transversely across the door opening 6 as shown in Figs. 2 and 3 and then the latch 14 carried by the end beam 10 may be moved into engagement with a keeper 15 thus releasably holding the frame in a set position.

The receiving member comprises an elongated fixed jaw 16 having a body 17 at its rear end extending inwardly at right angles thereto as shown in Fig. 1. This body 17 is fixed upon the lower horizontal beam 12 of the frame and is reinforced by the brace 18 connected thereto in any desired manner which is also connected to the lower beam 12. By referring to the several figures of the drawing it will be noted that the receiving member is carried adjacent one end of the frame, while the delivering member is 85 carried adjacent the opposite end of the frame. The body 17 of the fixed jaw 16 is reinforced by a hook 19, this hook 19 being secured as indicated at 20 to the upper beam 11 of the frame and being connected by the 90 eye 21 to the body 17.

The movable jaw 22 is not as long as the fixed jaw 16. A coiled spring 23 is connected to the inner end of the movable jaw 22 and is also connected to the body 17. 100 A bowed leaf spring 24 is fixed to the jaw 16 and to the movable jaw 22 and the springs 23 and 24 tend to force the movable jaw toward the fixed jaw. However, when the movable jaw is in a set position as indicated 105 in Fig. 1 the inner end thereof will fit within the notch 25 formed in the fixed jaw adjacent the inner end thereof. Accordingly the leaf spring 24 will hold the inner end of the movable jaw within this notch. However, when a mail bag is delivered between the jaws, the inner end of the movable jaw 110

will be thrown from the notch 25 and then the coiled spring 23 will swing the movable jaw toward the fixed jaw, thus causing the mail bag to be held between the fixed jaw 5 and the movable jaw.

The delivering member comprises a fixed jaw, 26 which extends from a point intermediate the ends of the body 27, this body 27 extending at right angles thereto as shown in Fig. 1. The inner end of the body 27 is fixed upon the upper horizontal bar 11 of the supporting frame and is reinforced by the diagonally extending brace 28 connected thereto and also secured to the horizontal beam 11. This delivering member is also steadied by a hook 29, this hook being secured to the car 5 as shown at 30, while the opposite end thereof is connected by the eye 31 to the body 27.

20 A bowed leaf spring 32 is mounted upon the fixed jaw 26, while the elongated movable jaw 33 is carried by the opposite end of the spring 32. A coiled spring 34 is connected to the inner end of the movable jaw 33 and to the body 27 as shown in Fig. 1. It will be noted that the movable jaw 33 of the delivering member is carried upon the outer side of the fixed jaw, while the movable jaw 22 of the receiving member is 30 carried upon the inner side of the fixed jaw. It will therefore be noted that the movable jaw 33 of the delivering member will be normally forced toward the fixed jaw, although when the device is in position for 35 operation, a mail bag may be carried between the fixed jaw 26 and the movable jaw 33 as shown in dotted lines in Fig. 1.

When the device is to be used it may be 40 swung to extend into the interior of the car 5 and then the operator may deposit a mail bag between the jaws 26 and 33 of the delivering member. He may then swing the movable jaw 22 of the receiving member away from the fixed jaw 16 whereby the inner end of the movable jaw may be inserted 45 into the notch 25, thus causing a movable jaw to be held in a set position. The frame may then be swung to extend across the door opening 6 and latched in this position 50 whereupon the receiving and delivering members will project beyond the outer portions of the car 5 as shown in Fig. 1. When a mail bag is deposited between the jaws 16 and 22 of the receiving member, the movable jaw will be knocked from the notch 25 55 and will be swung to grip the mail bag to hold the same upon the fixed and movable jaws of the receiving member. Then the

mail bag may be pulled from between the movable and fixed jaws of the delivering member, whereupon the movable jaw 33 will engage the fixed jaw 26. The frame may then be swung into the interior of the car to allow the mail bag to be removed from between the jaws 16 and 22 of the receiving member and the device will then be in position for another operation. Any form of a station member may be employed for receiving and delivering bags of mail and it is not deemed necessary to illustrate such a structure in the disclosure of the present invention which relates specifically to the construction of the device carried by the railway car.

As only one particular form of the present invention has been herein illustrated and described it is obvious that minor changes may be made in the construction thereof without departing from the spirit of the invention as long as such changes do not exceed the scope of the invention as claimed.

What is claimed is:

1. In a device of the class described, the combination of a supporting frame, gripping members carried by said frame, each 85 gripping member comprising a fixed jaw having a body extending at right angles thereto, and fixed upon said frame, means for reinforcing said body, a movable jaw, a coil spring connected to the inner end of 90 the movable jaw and to said body, a bowed leaf spring connected to the fixed jaw and to the movable jaw, whereby the movable jaw is urged toward the fixed jaw.

2. In a device of the class described, the 95 combination of a supporting frame, a gripping member comprising a fixed jaw having a body extending at right angles thereto and connected to said frame, means for reinforcing said body, said fixed jaw having a notch 100 therein, a movable jaw, a bowed leaf spring connected to the fixed jaw and to the movable jaw, a coil spring connected to said body and to the inner end of the movable jaw, whereby the movable jaw may fit with- 105 in said notch to be held in a set position, although when the inner end is knocked from said notch said springs will swing the movable jaw toward the fixed jaw.

In testimony wherof I affix my signature 110 in presence of two witnesses.

CHARLES W. PIERCE.
